CONTROL SYSTEM

Gerhard P. Lessmann, Pittsburgh, Pa., assignor
to Westinghouse Electric Corporation, East
Pittsburgh, Pa., a corporation of Pennsylvania

Application August 10, 1945, Serial No. 610,123

11 Claims. (Cl. 86—35)

1

My invention relates, generally, to tension control systems, and it has reference, in particular, to tensioning devices and tension indicating devices for respectively subjecting a strip of material to tension, and indicating the degree of tension therein as the strip passes between adjacent work devices.

Generally stated, it is an object of my invention to provide a double-range tensiometer which is simple and inexpensive to manufacture, and is easy to operate.

More specifically, it is an object of my invention to provide for operating a single tensiometer for producing or indicating relatively high and relatively low values of tension.

Another object of my invention is to provide for increasing the operating range of tensiometers to provide for operation at high as well as low values of tension.

Yet another object of my invention is to provide a double-roll tensiometer wherein a strip of material may be operatively positioned for producing either high or low values of tension without having to thread the strip back and forth around the rolls.

Still another object of my invention is to provide a tensiometer which may be changed from a relatively high to a relatively low operating range of tension values without changing the inertia characteristics thereof.

It is also an object of my invention to provide for movably positioning the rolls of a double-roll tensiometer relative to each other in order to permit threading a strip in substantially a straight line between the rolls, and then, moving the rolls relative to one another to produce a double deflection of the strip.

An important object of my invention is to provide for movably positioning a pair of tension rolls in a double roll tensiometer for so operating in different positions with either one or both of the rolls engaging a strip of material that in each case the roll or rolls are maintained at an angle of from 30 to 60 degrees with the free path of the strip to be tensioned.

It is also another object of my invention to provide a double-roll tensiometer wherein the roll support may be rotated in one direction about an axis intermediate the axes of the rolls to permit straight threading of a strip between the rolls and then further rotated in the same direction to the operating position.

Other objects will in part be obvious, and will in part be explained hereinafter.

In practicing my invention in one of its forms,

2

a strip of material is subjected to a transverse force between adjacent roll stands by a tensiometer having a pair of spaced apart rolls rotatably mounted on a support which is itself rotatable about an axis parallel to and intermediate of the axes of the rolls. The support is detachably connected to fluid pressure or other suitable actuating means for biasing the rolls against the strip to produce a predetermined tension therein. 5 Regulating means responsive to the operating position of the rolls control the relative speed of the roll stands to maintain a predetermined tension in the strip. When the tensiometer is operated in the high-tension range, the strip passes over the upper roll in the usual manner. When it is operated in the low-tension range, the strip is first threaded between the rolls which are then rotated about a common axis so that the strip is doubly deflected by the rolls to maintain a Z or S-shaped loop and produce a lower tension therein for the same adjustment of the actuating and regulating means.

For a more complete understanding of the nature and scope of my invention, reference may be made to the following detailed description, which may be studied in connection with the accompanying drawings, in which:

Figure 1 is a diagrammatic view of a tension control system embodying the invention in one of its forms;

Figs. 2 and 3 are schematic views of the double-roll tensiometer showing one way of threading the strip for operating in the low-tension range;

Fig. 4 is a schematic view of the double-roll tensiometer showing another arrangement of the strip;

Fig. 5 is an enlarged partial side elevational view of a tensiometer such as is shown schematically in Fig. 1;

Fig. 6 is a sectional view taken along the line VI—VI of Fig. 5;

Fig. 7 is a sectional view taken along the line VII—VII of Fig. 5;

Fig. 8 is a partial diagrammatic view of a double-roll tensiometer showing an alternate form of connection between the support and pressure actuating means;

Fig. 9 is an enlarged end elevational view, partially in section, of a double-roll tensiometer illustrating a different embodiment of the invention;

Fig. 10 is an enlarged end elevational view of a double-roll tensiometer illustrating yet another embodiment of the invention; and

Fig. 11 is an enlarged partial front elevational

view of the double-roll tensiometer of Fig. 10 arranged for operation as a tension indicator.

Referring to Fig. 1, the reference numeral 10 may denote, generally, a tension control system wherein a tensiometer 11 is disposed to provide for deflecting a strip of material 12 as it passes in a direction from left to right between work devices such as the roll stands 14 and 15, to produce a predetermined tension therein.

The roll stand 15 may be provided with a driving motor 17 having an armature 18 and series field winding 19 connected to a source of direct-current power represented by the conductors 20, through suitable control means 22. The shunt field winding 23 of the motor may be connected through a rheostat 24 to a source of direct-current power represented by the conductors 26.

The roll stand 14 may be provided with a driving motor 28 having an armature 29 and series field winding 30 connected to the conductors 28 through suitable control means 32. In order to vary the relative speed of the roll stands, the shunt field winding 33 of the motor 28 may be energized from a source of variable voltage, such as the generator 34, which may be provided with an armature 35 connected to the shunt field winding 33 and a field winding 36. The field winding 36 may be energized from the conductors 26 through a control resistor 37 and a suitable regulator 38. The regulator may comprise, for example, a tapped resistor 39, which may be shunted by a number of spring contact fingers 38a, disposed to be actuated by a lever 40 upon the rotation of a cam 41 on a shaft extension 42.

In many applications different operating values of tension are necessary, which require a range of values greater than can be satisfactorily accommodated by varying the fluid pressure or spring force of the usual type of single roll tensiometer. In one application, for example, tensions of 30 to 300 pounds were desired for the rolling of thin strip or foil, and tensions of 450 to 4500 pounds were also desired for rolling heavier strip in the same mill.

In order to provide for tensioning the strip 12, over such a wide range, the tensiometer 11 may comprise a pair of tension rolls 43 and 44 movably mounted relative to each other, being either mounted in guides in a fixed support, or being, as shown, positioned on a support plate 45 which may be rotatably mounted by means of a shaft 46 about an axis substantially parallel to and transversely of the strip 12. Actuating means such as shown comprising a fluid pressure device 47 and a pressure regulator 48 may be provided for applying a substantially constant torque to the support plate 45 for biasing the roll 43 against the strip 12.

In order to maintain the tension in the strip 12 substantially constant, suitable means may be provided for controlling the regulator 38 in response to movement of the support plate 45 and strip engaging roll 43. For example, a synchrotie system comprising a transmitter 50 and a receiver 52 may be provided for operatively connecting the tensiometer shaft 46 to the shaft extension 42, which effects operation of the spring contacts 38a, of the regulator 38 to vary the speed of the motor 28 by cutting in or out more of the control resistor 39 to speed up or slow down the driving motor 28 whenever the tension in the strip 12 increases above or decreases below the predetermined value.

When it is desired to operate in the high tension range the strip passes over the upper roll

43 as shown in Fig. 1. If the angles the strip makes with the horizontal at the stands 14 and 15 are α and β , the angle between the horizontal or free path of the strips and a plane through the axes of the roll 43 and the shaft 46 is θ , it may be shown that the moment M_s about the shaft 46 in the high tension arrangement shown in Fig. 1, due to a tension T in the strip, is approximately

$$10 \quad 2TR \cos \left(\theta + \frac{\alpha - \beta}{2} \right)$$

where R is the radial distance between the axis of the roll engaging the strip and the shaft 46. With the angles α and β ranging from 2 to 7 degrees, and θ in the neighborhood of 35 to 60 degrees, which are values commonly encountered in practice, this means that

$$15 \quad M_s \approx 2TR \cos \left(\theta + \frac{\alpha - \beta}{2} \right)$$

20 When operating in the low tension range the strip may be threaded about the rolls as shown in Figs. 3 or 4, whereby the moment about the shaft 46 due to the tension T of the strip is greatly increased, so that conversely a lower tension is produced by a given fluid pressure or spring force which biases the rolls against the strip. For example, referring to Fig. 4, it may be seen that the resultant force P exerted by the strip on each roll is approximately $2T$. The moment M_D exerted by the strip about the shaft 46 in the double roll application approximates $4T\gamma$ where γ is the perpendicular distance of the force P from the shaft 46. Since the value of γ may be approximately one half of the term

$$30 \quad R \cos \left(\theta + \frac{\alpha - \beta}{2} \right)$$

35 in the high tension arrangement, this means that $M_D \approx 10M_s$. The value would approximate $6M_s$ for the arrangement shown in Fig. 3. It may be made even higher than $10M_s$ for an arrangement similar to that of Fig. 4 by so moving the rolls relative to each other as to decrease the included angle between the portions of the strip on each side of the rolls.

40 In order to provide for operating the strip 11 at widely separated values of tension, the mechanical construction of the tensiometer may take many different forms. One of these may be such as shown in Figs. 5 and 6. It will be seen from these figures that the rolls 43 and 44 may be rotatably mounted on shafts 62 and 63, respectively, which may be supported by a single support plate 45, or which may extend between spaced support plates 45 and 64, as shown. The support plates may be rotatably mounted by means such as the shaft 46, which supports the plate 45 and extends through a sleeve 67 rotatably mounted in suitable bearings 68 and 69. The plate 64 may be rotatably supported by means of a rotatable shaft 65.

45 The support plate 45 may be operatively connected to the sleeve 67 by means of latches 70 and 71, which may be pivotally mounted adjacent the periphery of the support plate 45 for positioning in recesses 73 in the periphery of a flange 74 on the sleeve 67. The latch 71 may be provided with a handle 75, and may be operatively connected to the latch 70 by suitable means such as the lever mechanism 76, so that both of the latches may be operated simultaneously. The positions of the shafts 62 and 63 and the latches 71 may be such that the operating angle θ of the axis or axes of the roll or rolls, relative to the

free path position of the strip, in this case the horizontal, is approximately 35 to 60 degrees.

The fluid pressure means 47 may be operatively connected to the rolls by being connected to the flange 74 in any suitable manner, such as by means of a clevis 78, for transmitting the strip tensioning force to the rolls 43 and 44 through the latches 70 and 71. When it is desired to thread the strip about the rolls, the handle 75 may be operated to release the latches 70 and 71, so that the support plate 45 may be rotated in a counterclockwise direction about 120 degrees. The strip 12 may then be passed directly between the rolls as shown in Fig. 2, and upon return of the support plate to the position shown in Fig. 3, the strip will be threaded over the roll 43 and beneath the roll 44. If desired, the strip may be fed between the rolls without first rotating the plate 45, so that upon subsequent rotation of the plate 45 the roll 44 will occupy the upper position.

For the purpose of facilitating threading of the strip, means such as the motor 80 may be utilized either in conjunction with or in place of the latch mechanism for providing relative rotation of the support plate 45 and flange 74. The motor 80 may, for example, be mounted on a bracket 82 secured to the sleeve 67 and provided with a worm gear 83 for engaging a gear segment 84 mounted on the shaft 46. Normally the worm gear and segment provide a locking relation between the shaft 46 and the sleeve 67. The motor may be controlled in any suitable manner to rotate the shaft 46 relative to the sleeve for threading and then return it to the desired operating position to tension the strip.

When operating in the high tension range the strip 12 is merely passed over the upper roll 43 as shown in Fig. 1, and the tension control system operates in the usual manner to bias the roll 43 against the strip for maintaining the desired tension. When, however, it is desired to operate the tensiometer in the low tension range, the plate may be rotated 120 to 180 degrees whereupon the strip 12 may be passed directly between the rolls 43 and 44 as shown in Fig. 2. The support plate 45 may then be rotated in a clockwise direction through 120 to 180 degrees so that the rolls 43 and 44 substantially change positions. In this position the strip 12 is doubly deflected from its free path so that the restoring force produced for a given tension in the strip is much greater than that exerted by the strip 12 when it is disposed as shown in Fig. 1. For the arrangement shown in Fig. 4, the plate is rotated in a counterclockwise direction after passing the strip between its rolls. Accordingly, the tensiometer may be operated with the same pressure in the fluid pressure means 47, and with the regulator 38 adjusted the same as for the roll arrangement shown in Fig. 1, and yet maintain a much lower tension in the strip by reason of the increased reaction effect of the strip tension.

Referring to Fig. 8, a different embodiment of the invention is shown wherein the shaft extension 42 which connects the tensiometer to the regulator 38, may be operatively connected to the shaft 46 of the tensiometer by means of a differential device 86 having a pair of planetary gears mounted in a rotatable housing 87. The fluid pressure means 47 may be operatively connected to the support plate 45 of the rolls 43 and 44 by means such as the clevis 88 and pin 89, so as to be readily detachable therefrom.

When it is desired to thread a strip of material about the rolls 43 and 44, the fluid pressure means may be disconnected from the support plate 45 by removing the pin 89, and the shaft extension 5 42 may be locked in position by means of a suitable brake device 90. The support plate 45 may now be rotated through about 120 to 180 degrees in a counterclockwise direction by operating the handle 92 of the housing 87, whereupon the strip 12 may be passed directly between the rolls 43 and 44. The support plate 45 may then be returned to its original position by actuating the handle 92, whereupon the strip is doubly deflected and the fluid pressure means may be reconnected to the support plate 45 by replacing the pin 89 in the clevis 88. When the brake device 90 is released, the tensiometer is then ready for operation. When operation in the high tension range is desired, the strip 12 is merely passed over the upper roll 43 in the manner shown in Fig. 1 of the drawing.

In Fig. 9 a further modification of the invention is shown wherein the tensiometer rolls 43 and 44 may be rotatably supported by the shaft 46 by 25 means of a support plate 93 provided with oppositely positioned knife-edge bearings 94 and 95 for engaging a knife edge 96 of the actuating means 97.

The actuating means 97 may, for example, 30 comprise an upright shaft 98 having a collar 99 adjacent the upper end for engaging a spring 100 which biases the shaft upwardly. The lower end of the shaft may be provided with suitable damping means being, for example, provided with a 35 piston 101 having bypass openings 102, and which may operate in a cylinder 103 containing a suitable fluid such as oil 104.

In order to eliminate the necessity for back and forth rotation of the support plate 93, provision 40 may be made for rotating the support plate in a clockwise direction only, in order to facilitate positioning the strip without having to thread it around the rolls 43 and 44, when operating in the low tension range. The actuating means 97 may, for example, be pivotally mounted 45 between a pair of spaced upright arms 105 on a support member, and means such as the spring 106 utilized for normally biasing the upper end of the actuating means toward the support plate. 50 The support plate 93 may be provided with a double cam surface 108 about the periphery for engaging a guide roller 110.

The cam surface may be so arranged that when the support plate 93 is rotated in a clockwise direction, the knife edge 96 separates from the knife-edge bearing 94 and the actuating means 97 is tilted so that the knife-edge bearing 96 clears the tension roll 44 and the opposite knife-edge bearing 95, and then drops into position for engaging the knife-edge bearing 95. Thus the strip 12 may be fed directly between the rolls 43 and 44 and the support plate 93 may be then rotated through 180 degrees to produce a double deflection in the strip, whereupon the 65 knife edge 96 will be positioned for engagement with the knife-edge bearing 95 for applying the tensioning force to the rolls for operation in the low tension range.

Referring to Figs. 10 and 11, the reference 70 numeral 115 may denote, generally, a spring-operated tensiometer of the double-roll type. In this modification of the invention the tension rolls 43 and 44 may be mounted on a support plate 116, which may be rotatably mounted on a shaft 46. When such a tensiometer is used for

tensioning relatively narrow strip, the rolls need be supported at the one end only and they may be open at the other end. Accordingly, the strip may be readily threaded about the rolls for operation in the low tension range from the open ends of the rolls after it has been passed between both of the roll stands.

The support plate 116 may be provided with a suitable bearing 120 adjacent the periphery for engaging a knife edge 121 on a movable rod or shaft 122, which may be biased upwardly by means of a spring 123 for biasing the rolls against the strip. The lower end of the shaft 122 may be connected to a piston 125 in a dash-pot cylinder 126 mounted on a support 127 by means of knife-edge bearings 128 on opposite sides thereof. The tensiometer 115 may be operatively connected to regulating means such as described in connection with the system of Fig. 1 for regulating tension in a strip, or may be connected to indicating means 130 to indicate the tension in a strip of material. The connection to the indicating means may be effected in any suitable manner, such as by means of synchrotric devices 131 and 132 through a gear segment 133 connected to the shaft 46. The tension indicating means 130 may be provided with a single dial 134 having a double scale for indicating tensions in both the high and low ranges, since the different methods of threading the strip over the rolls change the force acting on the spring 123 by reason of the strip tension, and thus change the roll position. The indicating means follows changes in the roll position since the tension is proportional to the roll position in spring actuated tensiometers.

From the above description and the accompanying drawings, it will be apparent that I have provided, in a simple and effective manner, for operating tensiometers at values of tension which differ widely from each other. According to the several embodiments of my invention, the tensiometers may be easily changed from the high to the low scale without requiring threading of the strip around the tension rolls in different directions. Since the same moving parts are used in both the high and low tension scales, the inertia characteristics of my double-range tensiometer are the same for both ranges of tension, and the tensiometer is rendered more accurate over a wider range of values. Operation of the tensiometer in the most suitable operating position is effected for both high and low values of tensions.

Since certain changes may be made in the above-described construction and different embodiments of the invention may be made without departing from the spirit and scope thereof, it is intended that all the matter contained in the above description and shown in the accompanying drawings shall be considered as illustrative and not in a limiting sense.

I claim as my invention:

1. In a tensiometer for producing different values of tension in a strip between two work devices, a support plate rotatable about an axis transverse of and substantially parallel to the strip, means for applying a restoring torque to the support plate for maintaining it in a predetermined operating position, connecting means detachably connecting said means to the support to permit rotation of the support relative to said torque applying means, and a pair of substantially parallel spaced apart rolls rotatably supported by the support at one end only for rota-

tion about spaced apart axes substantially parallel to and on diametrically opposite sides of the axis of the support for engaging the strip either singly or together to provide a single or a double deflection in the strip for high and low values of tension.

2. A tensiometer comprising, support means mounted on a rotatable shaft, biasing means for applying a resilient restoring force to the shaft 10 for maintaining it in a predetermined operating position, a pair of rolls rotatably supported by shafts projecting from said support means and having spaced axes parallel to and on diametrically opposite sides of the shaft, and latch means 15 detachably connecting the support means and the biasing means whereby a strip of material may be threaded straight between the rolls and the support may be rotated relative to the biasing means so that the rolls positioned on opposite 20 sides of the strip of material produce a double deflection therein from the straight path therebetween.

3. A tensiometer comprising, a rotatable support, a pair of rolls mounted on the support in 25 fixed spacial relation to each other and on opposite sides of the axis of rotation of the support, a movable stop, latch means detachably connecting the support to the stop to permit rotation of the support relative to the stop, and means applying 30 a resilient restoring force to the stop to deflect a strip of material from a normal path.

4. A double range tensiometer comprising, stop means rotatable about an axis transverse of and substantially parallel to a strip of material, 35 means for applying a resilient operating torque to the stop means, a support rotatable about the axis of the stop means, a pair of rolls rotatably supported on the support means about axes parallel to and on opposite sides of the axis of 40 the stop means, and latch means connecting the support and the stop means operable to transmit the operating torque to the support and also permit rotation of the support relative to the stop means.

5. A tensiometer comprising, a support rotatable about an axis transverse of and parallel to a strip of material, a pair of tensiometer rolls for engaging the strip to doubly deflect it rotatably supported on the support about relatively fixed 50 spaced axes parallel to and displaced from the axis of rotation of the support, resilient torque means normally biased into operative connection with the support radially of the axis of rotation of the support, and means including a cam rotatable with the support for engaging guide means on the torque means to permit rotation of the support without interference from the torque means from a straight strip threading position 55 to an operating position to doubly deflect the strip.

6. A double range tensiometer for tensioning a strip of material passing between two work devices comprising, a support plate rotatable about 60 a substantially horizontal axis and having a projection adjacent one edge, means cooperative with the projection for applying a resilient restoring force to the support plate including an upright shaft biased to a predetermined position by a spring and provided with a damper and a pair of rolls projecting from and rotatably supported by the plate for either singly or jointly engaging a strip of material to be tensioned, the 65 axes of said rolls being on opposite sides of the axis of rotation of the support and in a plane 70

lying between 35 and 60 degrees to the pass line of the strip.

7. In a double-roll tensiometer, a rotatable sleeve having a flange at one end, means connected to the flange for applying a resilient restoring torque for retaining the sleeve in an operating position, a support rotatably mounted on a shaft extending through the sleeve, driving means operatively connecting the sleeve and shaft for transmitting torque between the rotatable sleeve and the support and also rotating the support relative to the sleeve, and a pair of tension rolls for engaging opposite sides of a strip to be tensioned positioned on the support on opposite sides of the shaft.

8. In a tensiometer, a support plate rotatably mounted on a shaft, a pair of spaced apart tension rolls positioned on the support for engaging and deflecting a strip to be tensioned in the operating position, means detachably connected to the support for applying a resilient tensioning force to the support, a shaft extension for connection to a regulator, means for braking said shaft extension, and means including a differential connecting the shaft and shaft extension for rotating the support for threading a strip between the rolls and returning it to the operating position.

9. The combination in a double-range tensiometer of upper and lower tension rolls disposed in fixed spaced relation to engage the lower and upper sides respectively of a strip to produce a double deflection therein, the axes of said rolls lying in a plane inclined between 35 to 60 degrees to the free path of the strip, support means rotatable about an axis parallel to and transverse of the strip intermediate the longitudinal axes of the rolls for positioning the rolls, biasing means, and means detachably connecting the biasing

means to the support for applying a resilient restoring torque to the support means.

5 10. In a double-roll tensiometer, a pair of spaced tension rolls, means for producing a resilient biasing force comprising an upright movable shaft having a dashpot damper.

11. A tensiometer device comprising, a rotatable support having a definite axis of rotation, a pair of rolls rotatably mounted on the support 15 in parallel fixed spaced relation to each other and on opposite sides of the axis of rotation of the support, a rotatable member coaxial with the support, biasing means operatively connected to the rotatable member, and connecting means selectively operable to one position to lock the support and rotatable member in fixed rotational relation relative to each other for biasing the support to a position in which the rolls doubly deflect a strip of material from a normal path between the rolls, and to another position to permit rotation of the support relative to the rotatable member.
